The ornamental design for a multiple air brush tool station, as shown and described.

DESCRIPTION

FIG. 1 is a perspective view of a multiple air brush tool station showing my new design;

FIG. 2 is a top plan view thereof;

FIG. 3 is a front plan view thereof;

FIG. 4 is a bottom elevational view thereof;

FIG. 5 is a rear elevational view thereof;

FIG. 6 is a right side elevational view thereof; and,

FIG. 7 is a left side elevational view thereof.

The paint brush, airbrush and hose coupling fragments depicted by means of broken lines in FIG. 1 have been shown for illustrative purposes only and form no part of the claimed design.
